(57) **CLAIM**

An ornamental design for a vehicle fog lamp, as shown and described.

DESCRIPTION

FIG. 1 is a left side elevational view of a left vehicle fog lamp (the right vehicle fog lamp being a minor image and is not shown);

FIG. 2 is right side elevational view of the vehicle fog lamp;

FIG. 3 is a front elevational view of the vehicle fog lamp;

FIG. 4 is a rear elevational view of the vehicle fog lamp;

FIG. 5 is a top plan view of the vehicle fog lamp;

FIG. 6 is a bottom plan view of the vehicle fog lamp; and,

FIG. 7 is a perspective view of the vehicle fog lamp.
